FIG. 1

FIG. 2

FIG. 6

FIG. 3

FIG. 4

FIG. 5

FIGURE 1 is a front and left side perspective view of a portable ironing press or the like showing my new design;

FIGURE 2 is a rear and left side perspective view thereof;

FIGURE 3 is a left side elevational view thereof showing the pressing head closed upon the buck;

FIGURE 4 is a side elevational view generally similar to FIGURE 3 and showing the pressing head separated from the buck;

FIGURE 5 is a bottom view thereof; and

FIGURE 6 is a front and left side perspective view of the portable ironing press or the like design shown in FIGURE 1 wherein portions of the top surface of the pressing head operating handle have a wood-grained ornamental appearance.

The dominant features of my design for a portable iron-

ing press or the like reside in the portions shown in full lines.

I claim:

The ornamental design for a portable ironing press or the like, substantially as shown and described.
